CALL BOARD

Zenas A. Bump, Fresno, Calif.

Application February 24, 1953, Serial No. 338,536

7 Claims. (Cl. 116—135)

1

The present invention relates to message racks of the general type known in the trade as "call boards" and more particularly to such a rack having improved production, assembly, operating and adjustment characteristics.

In offices, factories and the like having extensive personnel, it frequently is desirable to have a central location at which it can speedily be determined which individuals are present and the anticipated arrival times for those who are absent. Although conventional time card racks for time clocks may permit the ascertaining of those present by careful selection of the cards and their inspection, they do not suggest anticipated arrival or return times. In small offices, a secretary is sometimes charged with the responsibility of knowing who is present and the anticipated arrival times for those who are absent. This is an onerous task, at best, and entirely impractical where many individuals are involved. Bulletin boards and call boards have heretofore been employed for the purpose but have generally been inconvenient to employ and unreliable because of omissions by the individuals involved properly to record the requisite information.

An object of the present invention is, therefore, to provide an improved call board on which desired information can be so easily designated that individuals involved do not hesitate to maintain the same in accurate condition.

Another object is to provide a call board conveniently and easily controlled to designate the presence or absence of numerous individuals and the anticipated arrival or return time of those who are absent.

Another object is to provide such a call board that is readily modified to designate selected indicia of any character whatsoever that can be visually represented on cards insertable for the purpose.

Another object is to provide a device of the character described that can be quickly and easily expanded or contracted to accommodate varied capacity requirements.

Other objects are to provide improved elements and arrangements thereof in a device of the character described that are economical to produce, convenient and easy to assemble or disassemble, readily adjustable, durable, and fully effective in accomplishing the intended purposes.

Still further objects and advantages will become apparent in the subsequent description in the specification.

Referring to the drawings:

2

Fig. 1 is a plan view of a call board embodying the principles of the present invention.

Fig. 2 is a front elevation of the call board.

Fig. 3 is a vertical section through the call board taken on line 3—3 in Fig. 2.

Fig. 4 is a section similar to Fig. 3 but with central portions thereof removed for illustrative convenience.

Fig. 5 is a fragmentary front elevation of one end of the call board with its component parts in exploded relation for purposes of identification.

Fig. 6 is an enlarged fragmentary front elevation of time channel members and mounting plates therefor utilized in the device of the present invention.

Fig. 7 is a horizontal section through one end of the call board taken on line 7—7 in Fig. 2.

Fig. 8 is a view similar to Fig. 7 but with the members in disassembled and spaced relation.

Fig. 9 is a perspective of the portion of the call board shown in Fig. 8 with the elements in similar disassembled relation.

Fig. 10 is an enlarged vertical transverse section through the time channels and time cards, as viewed from line 10—10 in Fig. 2.

Referring in greater detail to the drawings:

The call board on the instant invention is preferably supported on a rectangular base member 10 formed of sheet metal, plastic or other suitable material having a platform 11 held in an elevated position by integral vertical side and end walls 12 and 13 respectively. The lower edges of the walls 12 and 13 terminate in a common plane parallel to the platform and are adapted to rest on a flat horizontal surface, such as a table top, with the platform spaced horizontally thereabove.

A pair of substantially identical molded, cast, or otherwise formed, standards 14 are mounted at opposite ends of the platform 11 as by screws 16 extended upwardly through the platform and embedded in the standards. The standards each provide an elongated foot 17 tightened downwardly against the platform in substantially parallel relation to its respectively adjacent end of the platform. A pair of elongated flanges 18 are provided in substantially right angular relation to each foot and upwardly extended therefrom intermediate opposite sides of the platform. Each pair of flanges defines a groove or channel 19 therebetween and with the standards mounted, as shown, the channels are in spaced juxtaposition. The channels are preferably, but not necessarily, provided with spaced constricted portions, as best shown in Fig. 4.

The standards 14 are employed to receive and support card holders 20 and a notice board 21 therebetween in vertically extended positions. These are conveniently and effectively mounted between the standards by providing a pair of auxiliary channel members 23 slidably fitted to the grooves 19. The channel members are formed of transversely return bent elongated strips of sheet metal providing inwardly disposed channels.

The holders 20 each comprise a pair of elongated strips of sheet material having return bent side edges 28 and flat central web portions 29. Pairs of such strips are secured together in back to back spaced relation by a rivet 30 passed therethrough adjacent to each end thereof having a spacer or washer 31 in circumscribing relation thereto intermediate the web portions.

Any desired number of pairs of mounting plates 32 are provided to retain the time holders in parallel edgewardsly vertically spaced relation. Each pair consists of a mounting plate edgewardsly fitted into a channel member 23. When more than one plate is employed in a channel member, as illustrated, such plates are arranged in endwardly abutting relation. The mounting plates provide inwardly projected edges which are notched at 33 in corresponding elevationally spaced relation slidably to receive the spacers 31 of the rivets 30. To assemble the holders 20, a number thereof equal to the number of notches 33 in a given mounting plate 32 are arranged in parallel spaced relation. A mounting plate is slid between the strips at the corresponding ends of the plurality of holders with the spacers 31 received in the notches. A companion mounting plate is similarly fitted between the strips at the opposite ends of the holders with the spacers likewise received in the notches. A plurality of pairs of mounting plates and their respective card holders are conveniently assembled by fitting corresponding plates of each pair in endwardly abutting relation into the channel members 23. So assembled, the channel members, mounting plates and card holders may be lifted, held in assembled relation by pressing inwardly on the channel members, and the whole retained in dependable assembly by sliding the channel members downwardly between the flanges 18 in the standards 14.

Substantially rectangular cards 37 bearing any desired indicia 38 are slidably fitted between the return bent side edges 28 of the holders 20. In the most popular commercial models of the subject invention, the cards bear indicia representative of the working hours of the day, as shown, and have the word "in" designated thereon for purposes soon to become apparent. Name cards 39 are preferably slidably fitted between the side edges of the holders at opposite ends of the indicia cards 37 whereby individual employees or the like may be designated. Different names are usually designated at opposite each of the indicia cards 37 to increase the capacity of the board.

Peripherally interrupted annular pointers 40 of resilient plastic, metal, or the like are slidably mounted on the oppositely disposed, adjacent, return bent side edges 28 of the holders 20, as best shown in Fig. 10, the adjacent ends of the pointers at the peripheral interruptions being slidably engaged with the indicia cards 37. The ends of the pointers are preferably somewhat pointed, as shown in Fig. 2, more accurately to designate indicia on the cards 37. The indicia cards and the name cards preferably bear the

5

10

same indicia on opposite sides of the call board but in reverse order as viewed. Thus said cards will read from left to right on one side of the call board in the same manner as the cards on the opposite side of the call board read from right to left. It will be seen, that when a pointer is located to designate selected indicia on a card at one side of the call board, it will automatically designate the same indicia on the card on the opposite side thereof.

It will be recalled that different names are designated at opposite ends of the indicia cards 37 so that each indicia card is useable for two individuals. The two pointers 40 registerable with each indicia card are arranged with one above its card and the other below. So as to designate which pointer represents a time of return for which individual the words "In" are arranged adjacent to opposite edges of the indicia cards. The pointer adjacent to the same edge of the card as the word "In," designates the arrival time for the individual whose name card 39 is adjacent to the end of the indicia card on which said word "In" is designated. Thus, as shown in Fig. 2, the pointers 40 above their respective indicia cards 37 designate arrival times for the individuals having name cards 39 at the left of the indicia cards and the lower pointers such times for the individuals having name cards at the right thereof.

The notice board 21 consists of a flat rectangular plate having parallel end edges so spaced as to be slidably receivable in the channel members 23 upwardly extended from the standards 14. A clip 45 is located against each face of the notice board 21 and riveted thereto as at 46 so that notices, letters, telegrams, or the like not shown, may be supported on the board for convenient observation by those concerned. In assembled relation, the notice board is rested in the channel members 23 on the upper ends of the mounting plates 32.

Operation

The operation and utility of the present invention are believed to be apparent and are briefly summarized at this point. The call board is used principally in offices, factories or the like where it is desired to indicate actual or anticipated arrival and/or departure times for a plurality of individuals. In the use of the call board in a particular office, appropriate indicia cards 37 are inserted into the holders 20 to show appropriate time spans or the like. Name cards 39 are placed in the holders at opposite ends of the indicia cards and have the names of the individuals designated thereon who are served by the office and whose presence or absence and time of return are to be indicated on the board.

As the individuals designated on the name cards 39 arrive at an office equipped with the subject invention, they move their respective pointers 40 to alignment with the adjacent words "In" of their respective indicia cards 37. Upon leaving the office, they move their pointers to alignment with a represented time at which they expect to return to the office. It is thus possible at a glance to determine which individuals are in the office, which are out of the office, and the expected times of return for the absent individuals. Any urgent messages may be called to the attention of any individual whose name is designated on the name cards 39 by inserting the same under the clips 45. While the subject invention has been described in terms of the designation of the presence or absence of individuals and the anticipated

pated time of return of those who are absent, it will be clearly apparent that cards of entirely different character may be substituted for those described to accomplish other notice, message, or recording functions. The essence of the present invention does not reside in the particular indicia employed on the cards but rather in the structure provided which makes possible the superior results attained.

As previously described, the cards 37 and 39, pointers 40, holders 20, mounting plates 32, and channel members 23 are speedily and easily assembled and slidably inserted between the flanges 18 in the standards 14 where they are dependably held in desired assembly. The plate 44 may be conveniently inserted in the upwardly extended ends of the channel members 23 and as readily removed.

The capacity of the call board is easily increased, by substituting longer channel members 23 and inserting additional sets of mounting plates 32 and their respective holders 20 therein. Somewhat similarly, any unused indicia cards 37, name cards 39 and their respective holders 20 may be removed by sliding their mounting plates 32 upwardly from the channel members 23 subsequent to removal of the notice board 21. The return of the notice board after removal of the unused holders and cards and the slideable depressing of the plate downwardly against the uppermost holder, assures the maintenance of the call board in neat and attractive condition.

The device of the present invention is economical to produce, durable, fully adjustable, and effectively accomplishes its intended purposes.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. A call board comprising a pair of spaced standards, a pair of channel members releasably mounted in facing relation in the standards, elongated mounting plates slidably and releasably mounted in opposing relation in the channel members having edges extended therefrom, holding members having upper and lower edges, means releasably mounting the holding members in substantially parallel spaced relation between the extended edges of opposed plates in facing channels and constraining movement of the holding members and mounting plates to sliding movement in the channels, indicia cards, means releasably mounting the indicia cards on the holding members, mounting members releasably mounted on the extended edges of the plates in substantially parallel spaced relation and having upper and lower edges, indicia cards releasably borne by the mounting members, and pointers slidably mounted on the edges of the mounting members having ends disposed adjacent to the indicia cards.

2. A call board comprising a pair of spaced standards, a pair of channel members releasably mounted in substantially parallel facing relation in the standards, elongated mounting plates slidably and releasably mounted in opposing relation in the channel members having edges extended therefrom, holding members having upper

5 and lower edges and laterally disposed sides, means releasably mounting the holding members in substantially parallel spaced relation between the extended edges of opposed plates in facing channels and constraining movement of the holding members and mounting plates to sliding movement in the channels, indicia cards, means releasably mounting the indicia cards on the holding members against the laterally disposed sides thereof, mounting members releasably mounted on the extended edges of the plates in substantially parallel spaced relation and having upper and lower edges and laterally disposed sides, indicia cards releasably borne by the mounting members against the laterally disposed sides thereof, pointers slidably mounted on the edges of the mounting members having ends disposed adjacent to the indicia cards, and a substantially flat notice board having opposite ends 10 slidably fitted into the channel members and rested in stacked relation on the mounting plates.

3. A call board comprising a pair of erect standards mounted in substantially parallel relation and having a pair of facing channels therein; an elongated channel member releasably fitted into the channel of each standard and endwardly extended therefrom; elongated mounting plates releasably fitted edgewards into the channel members having in opposing relation edges 15 extended therefrom, the edges of said plates having notches in corresponding spaced relation therewith; a plurality of card holding members arranged in substantially parallel spaced relation each having opposite ends supported in corresponding notches of the opposing plates, each holding member comprising a pair of elongated strips having opposite ends fitted against opposite sides of the opposing plates and upper and lower edges outwardly return bent, and spacers 20 rested in the notches of the plates interconnecting the strips of each pair in substantially parallel spaced relation; and indicia cards releasably fitted between the return bent edges of the strips of the mounting members.

4. A call board comprising a pair of erect standards mounted in substantially parallel relation and having a pair of facing channels therein; an elongated channel member releasably fitted into the channel of each standard and endwardly extended therefrom; a plurality of mounting plates releasably fitted edgewards into each channel member in opposing positions relative to the facing channels and in endwardly abutting relation in each channel; the plurality of plates 25 in each channel member having edges extended therefrom and said edges of the plates having notches in corresponding spaced relation therewith; a plurality of card holding members arranged in substantially parallel spaced relation each having opposite ends supported in corresponding notches of the opposed plates, each holding member consisting of a pair of elongated strips having opposite ends fitted against opposite sides of the opposing plates and upper and lower edges outwardly return bent, and spacers 30 rested in the notches of the plates interconnecting the strips of each pair in substantially parallel spaced relation; indicia cards releasably fitted between the return bent edges of the strips of the card holding members; and pointers mounted for longitudinal slidable adjustable movement on the return bent edges of the strips.

5. A call board comprising a base, a pair of standards integral with the base having a pair of facing channels therein, an elongated channel

member slidably fitted to the channel of each standard, a pair of substantially rectangular plates of predetermined thickness each having an edge slidably fitted into a channel member and an opposite edge extended therefrom, the plates being disposed in a common plane and the extended edges thereof being notched in corresponding positions in spaced relation to the base, a substantially cylindrical spacer having opposite ends and of an axial length substantially equal to the predetermined thickness of the plates releasably rested in each notch, a pair of substantially rectangular strips of sheet material each secured against opposite ends of corresponding spacers located in corresponding notches of the mounting plates and interconnecting said spacers in fixed spaced relation, the pair of strips connected to opposite ends of the corresponding spacers having ends slidably fitted on opposite sides of the mounting plates and upper and lower edges outwardly return bent to define laterally disposed card receiving channels, indicia cards slidably fitted to the card receiving channels, name cards slidably fitted to the card receiving channels adjacent to the indicia cards, and a peripherally interrupted annular pointer slidably fitted over each adjacent pair of return bent edges of each pair of strips for adjustable movement longitudinally thereof and having opposite ends disposed adjacent to the indicia cards on opposite sides of its pair of strips.

6. A call board comprising a base, a pair of standards mounted on the base and upwardly extended therefrom in substantially parallel relation, each of the standards having a channel therein in substantially erect position and the channels being disposed in spaced juxtaposition; an elongated channel member slidably fitted into the channel of each standard; a substantially rectangular mounting plate slidably fitted into each channel member and having an edge extended therefrom providing vertically spaced notches, the plates being disposed in a common plane and their corresponding notches being in substantially horizontal alignment; holding members releasably supported in elevationally spaced substantially horizontal positions in the notches of the mounting plates, each holding member consisting of a pair of elongated substantially parallel strips of sheet material, and a pair of annular spacers secured between the strips at opposite ends thereof, the spacers being releasably rested in the notches of the mounting plates with their respectively adjacent ends of the strips slidably fitted on opposite sides of the mounting plates, each of the strips having an upper and a lower transverse edge outwardly return bent with respect to its opposite strip; indicia cards slid-

ably fitted between the return bent edges of the individual strips; and peripherally interrupted annular pointers of resilient material slidably fitted over the corresponding return bent edges of each pair of holding members having opposite ends slidably engaged with the indicia cards on opposite sides of their respective holding members.

7. A call board comprising a base, a pair of standards mounted on the base and upwardly extended therefrom in substantially parallel relation, each of the standards having a channel therein in substantially erect position and the channels being disposed in spaced juxtaposition; an elongated channel member slidably fitted into the channel of each standard; a substantially rectangular mounting plate slidably fitted into each channel member and having an edge extended therefrom providing vertically spaced notches, the plates being disposed in a common plane and their corresponding notches being in substantially horizontal alignment; holding members releasably supported in elevationally spaced substantially horizontal positions in the notches of the mounting plates, each holding member consisting of a pair of elongated substantially parallel strips of sheet material, and a pair of annular spacers secured between the strips at opposite ends thereof, the spacers being releasably rested in the notches of the mounting plates with their respectively adjacent ends of the strips slidably fitted on opposite sides of the mounting plates, each of the strips having an upper and a lower transverse edge outwardly return bent with respect to its opposite strip; indicia cards slidably fitted between the return bent edges of the individual strips; peripherally interrupted annular pointers of resilient material slidably fitted over the corresponding return bent edges of each pair of holding members having opposite ends slidably engaged with the indicia cards on opposite sides of their respective holding members; a notice board slidably fitted in the upwardly extended ends of the channel members and rested on the upper ends of the mounting plates; and clip means mounted on the notice board adapted releasably to hold messages against the notice board.
